CONTROL PYLON FOR A RIDING LAWN MOWER OR THE LIKE

Alfred J. Przybylowicz, Grosse Pointe Farms, and Douglas N. Cabell, Livonia, Mich., assignors to Moto-Mower, Inc., Oak Park, Mich., a corporation of Delaware

Filed Mar. 7, 1960, Ser. No. 59,642

Term of patent 3½ years

(Cl. D40—1)

FIG. 1

FIG. 3

FIG. 2

FIG. 4

FIG. 1 is an enlarged perspective view of the control pylon for a riding lawn mower from the rear and one side thereof with a broken line representation of the control levers being for purposes of illustration only;

FIG. 2 is an elevational view thereof of the side opposite that shown in FIG. 1;

FIG. 3 is a front elevational view thereof; and

FIG. 4 is a top plan view thereof.

We claim:

The ornamental design for a control pylon for a riding lawn mower or the like, substantially as shown and described.
